UNITED STATES PATENT OFFICE.

EDWIN BALL STIMPSON, OF BROOKLYN, NEW YORK.

PUNCHING-MACHINE.

1,052,527.

Specification of Letters Patent. Patented Feb. 11, 1913.

Application filed May 13, 1912. Serial No. 696,804.

To all whom it may concern:

Be it known that I, EDWIN B. STIMPSON, a citizen of the United States, residing at Brooklyn, in the county of Kings and State 5 of New York, have invented certain new and useful Improvements in Punching-Machines, of which the following is a specification.

My present invention relates to a punching machine and more particularly to means 10 for the ready adjustment of the punches of the machine and for their attachment and detachment relative to the cross-head. The machine on which I use this improvement 15 is that heretofore patented to me in United States Patent No. 978,506 of December 13, 1910.

The features and advantages of my present improvement will be understood by 20 those skilled in the art from an understanding of the following description in connection with the drawings. These show only one of the specific embodiments which my invention is adapted to take and in them 25 Figure 1 is a fragmentary transverse vertical section through the cross-head and bed plate of a punching machine similar to that of my aforesaid earlier patent, showing one of the sub-presses and punches in side elevation and further showing my improved 30 means for attaching the individual punches to the cross-head; Fig. 2 is a detail fragmentary view on a larger scale looking from left to right at the upper portion of Fig. 1; 35 and Fig. 3 is a vertical section on the line 3—3 in Fig. 2 looking in the direction of the arrows.

Describing now the specific devices of the drawings, 1 is the bed plate of the machine 40 having a longitudinal trough 2 whose rear wall 3 is lower than its front wall 4.

5 is one of the sub-presses having a general gooseneck shape. Its lower arm has a trough-fitting downwardly extending 45 projection 6 receivable between the sides of the trough 2. Said sub-presses can be adjusted along this trough and then locked in any given position of said adjustment by means shown in my earlier patent.

50 7 is a die suitably mounted in the lower arm of the sub-press, the axis of the die being vertical and said die being located over an opening through the lower arm of the sub-press to permit the punchings to 55 drop through as in my earlier patent.

The upper arm of the sub-press is pro-

vided with a sleeve 8 which guides the punch 9 for reciprocation in operative vertical alinement with the die 7.

10 is the cross-head of the machine from which the punch or punches 9 are suspended, said cross-head being in turn operatively supported for vertical reciprocation toward and away from the bed plate of the machine as in my earlier patent.

Referring now more particularly to my present improvements, 11 is a rib having a dovetail cross section secured lengthwise to the bottom of the cross-head by bolts 12.

13 is a slide which is slidably suspended from the rib 11 and for this purpose has a recess in its top which fits the dovetail cross section of said rib.

The punch 9 is operatively suspended 75 from the cross-head by means of this slide 13 and, whereas the drawings show only one sub-press 5, one punch 9 and one slide 13, it will be understood that there may be a plurality of sets of these parts in each machine as shown in my earlier patent.

The bottom of each slide 13 has an internally threaded hole tapped vertically up into it to receive an adjustment screw 14 whose head is located over the upper end of the punch 9.

15 is a set screw let in through the front of the slide 13 to engage the adjustment screw 14 and lock it in any given position of adjustment.

16 is a round trunnion pin in a hole which extends through the slide 13 from end to end and which passes through the upper end of the vertical hole that contains the adjustment screw 14. This pin 16 is long 90 so as to provide projecting ends or trunnions at the end of the slide 13. Said pin 16 is prevented from becoming displaced endwise by a cotter pin 17 passed through a suitable hole extending from front to back through the slide 13 and intermediately 95 through a hole in the trunnion pin 16 (compare Fig. 3).

18 is a member in the form of a pair of hooks 19 in spaced apart side by side relation connected at the bottom by a cross-piece 20. The upper ends of these hooks straddle the slide 13 and have eyes which receive into them the trunnion-ends of the pin 16 (compare Figs. 2 and 3), and thereby constitute the pivots from which the hook-member 18 depends from the slide.

The upper end of the punch 9 has an an-

nular recess to provide a reduced neck 21. The connecting piece 20 of the hook-member is vertically grooved at 22 to straddle this neck 21 of the punch and said piece 20 is further recessed at 23 (Fig. 3) to accommodate the head 24 of the punch when its neck 21 is contained in the aforesaid recess 22 (Fig. 2). Thus it will be noted that these recesses 21 and 23 in the cross-piece 20 provide a projection or step 25 which engages the underside of the head 24 of the punch.

The operation is as follows: When the parts have been assembled as shown and described, the up and down reciprocation of the cross-head 10 carries the punch 9 with it by reason of the connecting means comprising the slide 13 and the hook-member 18. This connecting means permits lateral play and mutual accommodation of the parts so that there is no tendency to jam the punch in its guide sleeve 8.

The screws 14 in the respective slides 13 on the given machine are adjusted by unscrewing the brass set screws 15 and then applying a screw driver to the slot 14a in the head of each screw 14. The object of the adjustment of the several screws 14 is to make the heads of all of them bear simultaneously on the heads of the punches which can be accomplished by adjusting the several screws to project for a greater or less distance below their sockets depending upon the differences in the length of the punches 35 due to wear, sharpening or otherwise.

The hook-member 18 obviously permits the punches to be inserted and removed very easily by the mere swinging of the member about its trunnions.

40 What I claim is:

1. In a punching machine the combination of a vertically reciprocating cross-head, a suitably guided punch having a reduced neck at its upper end, and connecting means between said cross-head and punch comprising a member supported from the cross-head having a pivoted hook-member which engages the reduced neck of the punch.

2. In a punching machine the combination of a vertically reciprocating cross-head, a suitably guided punch having a reduced neck at its upper end, and connecting means

between said cross-head and punch comprising a member supported from the cross-head having a pivoted hook-member depending therefrom, the lower or free end of said hook-member straddling the neck portion of the punch and projecting under the head of said punch. 55

3. In a punching machine the combination of a vertically reciprocating cross-head, a suitably guided punch having a reduced neck at its upper end, and connecting means between said cross-head and punch comprising a slide which is slidably supported from the bottom of the cross-head, said slide having a pivoted hook-member depending therefrom whose lower or free end straddles the neck portion of the punch and projects under its head. 60

65 4. In a punching machine the combination of a vertically reciprocating cross-head, a suitably guided punch having a reduced neck at its upper end, and connecting means between said cross-head and punch comprising a slide which is slidably supported from the bottom of the cross-head, said slide having a pivoted hook-member depending therefrom whose lower or free end straddles the neck portion of the punch and projects under its head, the bottom of said slide over the head of the punch having a vertical screw-threaded opening, and an adjusting screw in said opening. 70

75 5. In a punching machine the combination of a vertically reciprocating cross-head, a suitably guided punch having a reduced neck at its upper end, a slide which is slidably supported from the bottom of the cross-head, and a hook-member comprising a pair 80 of hooks which at their upper ends straddle the slide and are pivotally connected therewith and whose lower ends depend below the bottom of the slide and are connected by a cross-piece, said lower portion of the hook-member straddling the reduced neck of the punch and extending underneath its head. 85

90 In testimony whereof I affix my signature in presence of two witnesses.

EDWIN BALL STIMPSON.
